UNITED STATES PATENT OFFICE

GEORGE C. QUELCH, OF OAKMONT, PENNSYLVANIA, ASSIGNOR TO INTERNATIONAL OXYGEN COMPANY, OF NEWARK, NEW JERSEY, A CORPORATION OF NEW JERSEY

CUTTING TORCH

Application filed August 23, 1926. Serial No. 130,887.

My invention refers to improvements in the class of torches or burners for the purpose of cutting ferrous metals by the application of a jet of high pressure oxygen, subsequent to the action of a preliminary or preheating flame.

The use of such torches is widely extensive, utilizing various gases as acetylene, hydrogen, hydrocarbons, etc., with oxygen for preheating, controlled by various valves. In certain standard constructions a lever controlled valve is also utilized for control of the cutting oxygen supply, operable by the hand of the user while holding the torch.

In my invention I provide a fuel gas valve so combined or associated with the valve-actuating mechanism for the cutting oxygen supply, as to cooperate therewith to open the gas valve when the main oxygen supply is closed, and vice versa.

One preferred embodiment of the invention is shown in the accompanying drawings, in which:—

Fig. 1 is a view of a torch in side elevation provided with my invention;

Fig. 2 is an enlarged view of the valve mechanism at right angles to Fig. 1;

Fig. 3 is a longitudinal vertical section on the line III, III, of Fig. 1, further enlarged, showing the gas valve open;

Fig. 4 is a partial similar view showing the gas valve practically closed;

Fig. 5 is a plan view corresponding to Fig. 1, with the covering and levers removed.

The torch as a whole comprises a head A having a burner tip 2, to which through suitable ports or ducts, are supplied the cutting oxygen by pipe 3, the preheating oxygen by pipe 4, and the fuel gas by pipe 5, as is well understood by those familiar with the art.

The main oxygen supply for pipes 3 and 4 is by connection 6, the pre-heating oxygen through pipe 4 being regulated by valve stem 7, the cutting oxygen pipe 3 being connected for full volume supply beyond said valve. Gas is supplied to conduit 5 by connection 8 regulated by valve stem 9. It will be understood that the valves and their stems 7 and 9 are located at any convenient posi-

tion, and are usually incorporated with the main handle portion of the torch.

Ordinarily, the supply of cutting oxygen for pipe 3 is independently controlled by the operator through a valve O, adapted to be opened by a lever 10, pivotally mounted at 11 and operating within the hand grip shell 12 of the torch, as is well understood and practiced in connection with such torches. Such oxygen controlling valve is normally closed until the metal has been preheated by the preheating oxygen and fuel flame, produced by the issuance of the mixture through ducts arranged around the usual central cutting jet opening.

For the purpose of controlling the flow of fuel gas through pipe 5, I provide said pipe, or the fuel gas conduit at any point, with the valve B adapted to remain normally open when circulation is opened through the gas line, and to be closed or practically closed in connection with the opening of the main oxygen supply through pipe 3 to the central duct of cutting tip 2.

Valve B comprises a casing as shown, having connecting lugs or sockets 13 for pipe 5, a central bore or chamber 14 for the movable valve head 15, and communicating cross ports 16 for circulation of the gas.

Plunger 15 is normally retracted to open position by spring 17, bearing against the valve head or plunger 15 at one end and against the terminal closing plug 18 at the other. Said plug is in threaded engagement with the end of the valve casing, as at 19, and may be accurately adjusted to vary the tension of the spring.

At the other end a stem 20 extends through the casing, with a suitable bushing and packing as shown, and a lever 21 is pivoted at 22 between bearing lugs of the casing, and extends inwardly underneath the oxygen valve lever 10, as in Fig. 2.

By such construction and arrangement, when the valve lever 10 is depressed to open the cutting oxygen supply, the fuel gas valve plunger 15 is correspondingly depressed by its lever arm 21, substantially cutting off the fuel gas supply, as in Fig. 4. I prefer not to entirely cut off the fuel gas supply, so as

to always leave sufficient gas to provide a pilot light at the end of the burner tip, with a full supply for preheating when the valve is opened.

5 The desired movement of the valve plunger 15 may be easily regulated by the length of arm 21 and its point of engagement with lever 10, with the desired leverage action against the re-acting spring 17.

10 By such construction and arrangement there is no loss of time or of either oxygen or gas. The preheating application of the fuel gas and oxygen is continued until the metal is raised to the proper temperature, 15 when by the mere operation of the single lever 10 the fuel gas supply is automatically terminated or limited and the cutting oxygen supply is simultaneously commenced.

Likewise, at the termination of the cutting oxygen supply, if additional preheating is desired the torch is immediately ready for such further application, providing for continuous use without loss of time, so long as the main supply through valves 7 and 9 is 25 continued.

It will be understood, of course, that the 20 particular location of valve B is not necessarily in the position shown, but that it may be incorporated anywhere in the fuel supply line and in proper relation to the hand lever of the cutting oxygen supply for cooperation therewith.

The invention may be otherwise changed or varied by the skilled mechanic or builder; 35 to adapt it to different standard constructions of torch, or for other reasons, and it will be understood that the invention is not necessarily limited to the particular construction and arrangement shown.

40 Having described my invention, what I claim is:

1. In a cutting torch, the combination with a cutting tip and head having passageways for delivering heating and cutting gases, a 45 main oxygen supply conduit and a main gas supply conduit, a preheating oxygen conduit connected with the main oxygen conduit with an intervening valve, a cutting oxygen conduit connected with the main oxygen conduit with an intervening valve, a lever therefor, a gas supply conduit connected with the main gas conduit, a separable independently connected valve in the gas supply conduit having an outwardly projecting valve stem extension, and a lever therefor engaging said extension and in operative relation to the lever of the cutting oxygen conduit valve.

2. In a cutting torch, the combination with a cutting tip and head having passageways 60 for delivering heating and cutting gases, a main oxygen supply conduit and a main gas supply conduit, a preheating oxygen conduit connected with the main oxygen conduit with an intervening valve, a cutting oxygen conduit connected with the main oxygen conduit

with an intervening valve, a lever therefor, a gas supply conduit connected with the main gas conduit, a separate valve casing provided with a spring retracted valve in the gas supply conduit having an outwardly projecting extension, and a depressing lever therefor engaging said extension and extending inwardly against the lever of the cutting oxygen conduit valve under pressure of the spring retracted stem of said separate valve casing.

3. In combination, a cutting tip and head having passageways for heating and cutting gases, a main oxygen supply connection and a main gas supply connection each having a separate controlling valve, a preheating oxygen pipe and a cutting oxygen pipe connecting the main oxygen supply connection with the head, a gas supply pipe connecting the main gas supply connection with the head, an independent valve casing connected at each side with the cutting oxygen pipe having a plunger, stem and an operating lever, a valve in the gas supply pipe having an extended stem, an operating lever engaging the extended stem and the lever of the cutting oxygen valve, and a retracting spring in the casing normally pressing the plunger to open position and pressing its stem against its operating lever.

4. In a torch, the combination with a cutting tip and head and a handle portion having a main oxygen supply connection and a main gas supply connection, a preheating and a cutting oxygen pipe connecting the oxygen supply connection with the head, and a gas pipe connecting the gas supply connection with the head, of a chambered valve casing in the gas pipe line having ports communicating therewith, a plunger valve therein having an outwardly projecting stem and a re-acting spring, a depressing lever for the stem having a free terminal, and a control valve in the cutting oxygen pipe line having an operating lever engaging the terminal of said lever for closing the gas supply valve when the oxygen supply valve is opened, the re-acting spring normally exerting pressure by the stem against its depressing lever to hold it in contact against the inner side of the lever of the cutting oxygen control valve.

5. In a torch, the combination with a cutting tip and head and a handle portion having a main oxygen supply connection and a main gas supply connection, a preheating and a cutting oxygen pipe connecting the oxygen supply connection with the head, and a gas pipe connecting the gas supply connection with the head, of a chambered valve casing in the gas pipe line having ports communicating therewith, a plunger valve therein movable across said ports to vary their circulating area and having an outwardly projecting stem, a depressing lever for the stem pivoted on the valve casing and having a free terminal, a closing cap for the opposite

side of the casing threaded therin, a spring between said cap and the plunger valve exerting opening pressure on the valve and pressing its stem against said lever, and a control valve in the cutting oxygen pipe line having an operating lever engaging the terminal of said lever against the spring exerted pressure of the plunger valve stem.

6. The combination with a cutting torch
10 provided with an oxygen conduit and a gas conduit, and a valve controlling the oxygen supply having an actuating lever, of a valve controlling the gas supply having a retracting spring and a stem normally extended by said 15 spring, and an actuating arm for the gas supply valve engaging said stem and having a freely sliding terminal extending underneath and normally pressed by said spring against the oxygen valve lever for depression thereby to reduce the gas supply as the oxygen supply is increased.

In testimony whereof I hereunto affix my signature.
